The ornamental design for a vertical structural member for shelving, as shown and described.

DESCRIPTION

(21) Appl. No.: **29/393,272**

FIG. 1 is a perspective view of the vertical structural member for shelving of my new design;

(22) Filed: **Jun. 1, 2011**

FIG. 2 is a front elevational view thereof;
FIG. 3 is a rear elevational view thereof;

(51) **LOC (9) Cl. 08-05**

FIG. 4 is a left side elevational view thereof, a right side elevational view thereof being a mirror image of the left side elevational view;

(52) **U.S. Cl. D8/381**

FIG. 5 is a top plan view thereof;

(58) **Field of Classification Search** D8/394,

FIG. 6 is a bottom plan view thereof;

D8/381, 380, 373, 371, 366, 354, 349; D6/574,

FIG. 7 is a perspective view of the vertical structural member seen from its vertical position, corner side;

D6/511, 479, 478, 474, 466, 463, 436, 399;

FIG. 8 is a front elevational view of a partial rack assembly, seen from an outer side thereof, for showing coupling state with a horizontal structural member; and,

D25/132, 131, 126, 123; D23/267; 248/68.1,

FIG. 9 is a rear elevational view of a partial rack assembly, seen from an inner side thereof, for showing coupling state with a horizontal structural member.

248/65, 49, 243; 211/87.01, 191–193, 188,

The alternate long and two short dash lines shown in FIGS. 1–3 and 5–9 indicate that there is no particular length claimed.
